UNITED STATES PATENT OFFICE.

FREDERICK H. SHERMAN, OF WHITMAN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CUTTING-MACHINE.

1,279,595.

Specification of Letters Patent. Patented Sept. 24, 1918.

Application filed April 5, 1915. Serial No. 19,819.

To all whom it may concern:

Be it known that I, FREDERICK H. SHERMAN, a citizen of the United States, residing at Whitman, in the county of Plymouth and 5 State of Massachusetts, have invented certain Improvements in Cutting-Machines, of which the following description, in connection with the accompanying drawings, is a specification, like reference characters on the 10 drawings indicating like parts in the several figures.

This invention relates to machines and devices employed in the cutting of sheet material and particularly to means for maintaining the material to be cut in proper position 15 for the cutting operation or operations.

The invention is herein shown as embodied in a machine of the type known to the trade as the "clicking machine", but it will be understood that the invention, in its broader 20 aspects, is of general applicability in the cutting art.

In cutting sheet material which is supported upon a cutting block it is important 25 that the material should not move over the surface of the block during the cutting operation, and when several thicknesses of material are cut at one time it is also important 30 that the thicknesses of material should not move relatively to each other between the cutting operations.

The machine in which the invention is shown as embodied has come to be used quite extensively in the cutting of linings for shoes 35 and in the cutting of blanks from cloth and similar material which comes in sheets of uniform character, whereby several blanks may be cut at a single operation simply by superposing the layers of material and forcing 40 a die having the shape of the blank through these layers. In such work, as pointed out in the specification of United States Letters Patent to C. E. Howe, No. 1,070,133, granted August 12, 1913, for improvements in cutting machines, it is not only 45 important that the material to be cut be so held during and between the cutting operations that there will be no relative slipping of the superposed layers, but it is also important 50 that that part of the material which extends beyond the edge of the bed be so held as to prevent it from pulling the mate-

rial upon the bed over the edge, either under the action of its own weight or by reason of its being moved accidentally by the operator 55 in adjusting the die or other cutting means over the cutting block. In said Letters Patent to C. E. Howe is disclosed means for preventing both relative movement of the layers of material upon the block and movement of 60 the material over the block, and a general object of the present invention is an improvement in devices of the type disclosed in said Letters Patent.

In machines of the type shown in said Letters Patent to C. E. Howe and in the present application the length of the cutting surface of the cutting block is usually such that the operator can conveniently swing the presser member over the block and can conveniently reach the die, wherever located upon the block, the length of the block being so proportioned to its desired width that a presser member which will reach any point of the surface will not extend too far over 75 the front of the block. The cutting blocks in machines of the type herein shown are usually about 36 inches long and are rarely over 40 inches long. Material, such as cloth, from which shoe linings and blanks are cut 80 in the manner above described comes frequently in widths of 60 inches or more, and thus is wider than the greater dimension of the cutting block. It is desirable that the means for preventing the relative movement 85 of the material upon the cutting block be so constructed that it will handle conveniently any width of material which it is desired to cut, and an object of the invention is to provide improved holding means which 90 will operate upon material of any desired width.

A further object of the invention is to provide means for the purposes above specified which can easily and quickly be incorporated 95 in a machine of the type herein shown.

Another object of the invention is to provide means for the purposes above specified which, while it will accommodate and effectively hold material of any width, does not 100 occupy excessive floor space, and preferably does not materially, if at all, increase the required floor space for a machine of the type in which the invention is incorporated,

Other objects and important features of the invention will appear from the following description and claims when considered in connection with the accompanying drawings, in which,—

Figure 1 is a perspective view of a machine having embodied therein the present invention;

Fig. 2 is a detail of the treadle and connected parts;

Fig. 3 is a perspective detail showing one of the lateral supports for the clamping roller; and

Fig. 4 is a broken perspective of the movable clamp member showing the construction of the inner face of said member.

The machine in which the invention is shown as incorporated is of the type known to the trade as the "clicking machine" and is more fully illustrated and described in United States Letters Patent to Arthur Bates, No. 921,503, May 11, 1909, certain mechanisms not shown in said patent to Arthur Bates being illustrated and described in United States Letters Patent to H. H. Eaton, No. 1,004,757, October 3, 1911.

This machine comprises a cutting block 2 supported upon a table 3 carried upon a stand 4, and over this cutting block a presser member 6 is adapted to swing into different operative positions, said presser member being carried upon a post or plunger 10 mounted for vertical reciprocation and for oscillation about its vertical axis in bearings 12 and 14 in an overhanging arm 15 carried by the stand 4. The operator swings the presser member laterally into its different operative positions by a handle 36 which may also be depressed to actuate the mechanism for effecting the pressing operation.

As hereinabove pointed out, a common use to which machines of this type are now put is in cutting linings for shoe uppers, several thicknesses of lining material being laid one upon the other so that several blanks may be cut at one operation. This lining material, usually cloth, comes in bolts or rolls made up of a considerable length of material, so that a part of the material from which the linings are to be cut hangs over an edge of the cutting block. Moreover, it is frequently desired to cut the linings from material of a width considerably greater than that of the cutting block. The present invention aims to provide for the proper support of this material, both that which is upon the block and that which is to be operated upon later. To this end clamping means are provided which will clamp in position to be operated upon the portion of the material which is upon the block and is so constructed that it can handle not only material of the width of the cutting block but also material of any width, the support for the bolt or roll of material being so re-

lated to the clamping means that it will also handle conveniently material of a width greater than the cutting block.

The illustrated clamping means comprises a smooth-faced roll 40, constituting the stationary member of the clamp, said roll being located at the front of the machine and having pintles at its ends received in bearings in bracket slides 42. The slides 42 are provided with guideways 44 which receive guide members 46 upon bracket pins 48 clamped to the side of the table 3 by screws (not shown) which pass through slotted openings 50, whereby an adjustment of the distance of the roll 40 from the cutting block is permitted. The bracket slides 42 are provided with slots 52 through which extend clamp screws 54 by which said slides 42 are clamped upon the guides 46. The guideway 44 and the guides 46 are somewhat curved so that in its adjustment up and down the roll 40 may be made to clear the iron clamp 57 upon the cutting block 2.

The coöperating member 56 of the clamping means has an inwardly curved or concave face preferably provided with teeth or corrugations 58 whereby it may grip firmly the material curved over the surface of the roll. This member, which, for the sake of lightness and room, may be shorter than the roll 40, as shown, is arranged to be moved toward and away from the roll 40 and is normally held yieldingly in clamping relation to said roll. To permit the movement of the clamp member 56 into and out of clamping relation to the coöperating member 40 without interfering with the insertion between the clamp members of material wider than the clamping means the member 56 is arranged to swing about an axis below the support for that part of the material which extends below the clamping means. This material being supported in bulk in the illustrated construction in an open-ended trough 60 carried by brackets 62 so constructed that they may be hooked over parts of the stand 4 and may be held upon said stand by the weight of the trough and of the parts of the bracket which project in front of the stand. As shown, each bracket 62 comprises a hook 64 which hooks over one of the horizontal bars 66 of the stand 4 and a second hook 68 which hooks over the back of one of the legs 70 of the stand. It will be seen that these hooks are so arranged that the hook 68 is drawn against the leg 70 by the weight of the trough and of the forwardly projecting portions of the bracket, which tends to swing the hook 68 about the hook 64 as a fulcrum. The clamp member 56 is carried upon a supporting rod 72 bent so that it clears the trough 60 and extends back to a swinging support 74 fulcrumed upon the connecting rod 76 in the base of the machine. The rod 72 is adjustable in a

socket 78 in the support 74 and may be held in its different positions of adjustment by a set screw 80, or the socket 78 may be split and provided with a screw extending across 5 the opening, in the usual manner, to form a clamp embracing said rod.

The support 74 is formed as a yoke which has a bearing engagement upon the rod 76 upon each side of a clamp 82 by which an 10 arm 84 is clamped upon the rod 76, said arm 84 serving as a support for one end of a spring 86, the other end of which is connected to a collar 88 on the rod 72. The 15 spring 86 is so tensioned that it tends normally to hold the clamp member 56 in clamping relation to the clamp member 40. To hold the arm 84 firmly against the pull of the spring thereon when the clamp member 56 is being moved out of clamping relation 20 to the member 40, said arm has hooked therein a bolt 90 connected by a turn buckle 92 to a second bolt or rod 94 hooked over the cross rod 96 in the rear of the machine base. By the turn buckle 92 the tension of 25 the spring 86 may be adjusted. Projecting forwardly from the support 74 is a bracket 98 upon which a treadle 100 is clamped, the treadle and bracket arm having interlocking faces at the joint 102 so constructed and arranged that said treadle may be clamped upon the arm 98 in different positions of adjustment about the clamping bolt 104. The 30 support for the treadle in the construction shown is so related to other parts of the clamping mechanism that the treadle is positioned between the clamp member 56 and the rod 76.

Having fully described my invention, what I claim as new and desire to secure by 40 Letters Patent of the United States is:

1. In a machine for cutting flexible sheet material, a cutting block, and an open-ended clamp located outside the cutting surface of said block for clamping the material to be cut which projects beyond the edge of the block, said clamp having a smooth surface over which the material passes to the cutting block and from which it depends as the stock supply for successive operations.

2. In a machine of the class described, a cutting block, and a clamp located outside the cutting surface of said block, said clamp comprising a roll, and a member having a concave face shaped and arranged to coöperate with the convex surface of said roll.

3. In a machine of the class described, a cutting block, and an open-ended clamp located outside the cutting surface of said block for clamping the material to be cut which projects beyond the edge of the block, said clamp comprising two members, one of which is movable into and out of clamping relation to the other about an axis remote from the material engaging surface of said member, the construction and arrangement

being such that the movable member clamps the material against the side and upper face of the stationary member.

4. In a machine of the class described, a cutting block, and a clamp for clamping the material to be cut which projects beyond the edge of the block, said clamp comprising a roll, and a coöperating clamp member having a roughened concave clamping surface arranged to coöperate with the convex surface of the roll.

5. In a machine of the class described, a cutting block, and a clamp for clamping the material to be cut which projects beyond the edge of said block, said clamp comprising a roll located adjacent to the block and over which the material to be cut passes, and a coöperating clamp member having a concave surface arranged to coöperate with the convex surface of said roll.

6. In a machine of the class described, a cutting block, and a clamp for clamping the material to be cut which projects beyond the edge of said block, said clamp comprising a roll supported adjacent to said block, and a coöperating clamp member arranged to be swung into and out of coöoperative relation to said roll about an axis parallel to the axis of said roll, said member having a concave clamping face curved about an axis parallel to the axis of said roll.

7. In a machine of the class described, a cutting bed, an open-ended clamp for the material to be cut which projects beyond the edge of said bed, said clamp comprising a roll supported adjacent to a side of said bed, and a coöperating clamping member arranged to be swung into and out of clamping relation to said roll about an axis parallel to said roll, and means tending yieldingly to maintain said clamping member in operative relation to said roll.

8. In a machine of the class described, a cutting block, means for clamping the material to be cut which projects beyond the edge of said block, said means comprising a clamp member located adjacent to the block, and a second clamp member arranged to be swung into and out of coöoperative relation to said first member about an axis parallel to the edge of said block, means for yieldingly maintaining said members in coöperative clamping relation, and means for varying the clamping pressure.

9. In a machine of the class described, a cutting bed, a clamp for the material to be cut which projects beyond the edge of said bed, said clamp comprising a member adjacent to the side of said bed and a second member arranged to be swung into and out of clamping relation to said first member about an axis substantially parallel to the edge of said bed, and means comprising a treadle for effecting the outwardly swinging movement of said second-mentioned member.

10. In a machine of the class described, a cutting bed, an open-ended clamp for the material to be cut which projects beyond the edge of said bed, said clamp comprising a member adjacent to the side of said bed, a second member arranged to be swung into and out of operative relation to said first member about an axis substantially parallel to the edge of said bed, means for yieldingly 10 maintaining said clamping members in co-operative relation, and a treadle for moving said members into unclamping relation.

11. In a machine of the class described, a cutting block, means for clamping the material to be cut which projects beyond the edge of the block, said means comprising a clamp member extending along substantially the whole front edge of said block, and a co-operating clamp member arranged to be 20 swung into and out of co-operative relation to said first-mentioned clamp member, said co-operating clamp member extending along a portion only of the front edge of said block, both said clamp members being adjustable vertically to correspond with marked differences in the thickness of the work presented to the clamping means.

12. In a machine of the class described, a cutting bed, an open-ended clamp arranged 30 to clamp the material to be cut which projects beyond the edge of said bed, said clamp comprising co-operating members arranged for relative movement about an axis extending parallel to the edge of the cutting bed, 35 and supports for said members so shaped and arranged as to provide an open space below the clamping surfaces of said members for a material receiving trough, and a trough in said space.

40 13. In a machine of the class described, a cutting bed, an open-ended clamp arranged to clamp the material to be cut which projects beyond the edge of said bed, said clamp comprising co-operating members arranged 45 for relative movement about an axis extending parallel to the edge of the cutting bed, and supports for said members so shaped and arranged as provided an open space below the clamping surfaces of said members 50 for a material receiving trough, and an open-ended trough in said space.

14. In a machine of the class described, a cutting block, an open-ended clamp for clamping the material to be cut which projects beyond the edge of said block, and an open-ended trough for the material which extends below said clamp, said clamp comprising co-operating clamp members and supports for said members arranged to embrace 60 said trough.

15. In a machine of the class described, a cutting block, a presser member supported behind said cutting block and arranged to swing over said block into different operative relations thereto, an open-ended clamp 65

located in front of said block for clamping the material to be cut which projects beyond the front edge of said block, and a trough for receiving and supporting the free end of the material, one of said clamp members being supported above said trough, and the other clamp member being supported below said trough. 70

16. In a machine of the class described, a cutting bed, an open-ended clamp arranged to clamp the material to be cut which projects beyond the edge of said bed, and a trough for the free end of the material, said clamp comprising two members normally in co-operative clamping relation above said 80 trough and movable relatively to each other about an axis below said trough. 75

17. In a machine of the class described, a cutting bed, an open-ended clamp arranged to clamp the material to be cut which projects beyond the edge of said bed, and a trough for receiving and supporting the free end of said material, said clamp comprising two members supported for relative movement into and out of clamping relation to 90 each other, the support for one of said members extending over the outside of said trough. 85

18. In a machine of the class described, the combination with a cutting bed, and a supporting stand therefor having vertical and horizontal members, of a clamp arranged to clamp the material to be cut which projects beyond the edge of said bed, a material receiving trough below said clamp, and supporting means for said trough comprising a hook engaging a vertical member of said stand, and another hook engaging a horizontal member. 95 100

19. In a machine of the class described, a cutting block, a clamp for supporting the material to be cut which projects beyond the edge of said block, said clamp comprising a member adjacent to said block, and another member arranged to be swung into and out of operative relation to said first member about an axis below said block, and a treadle for swinging said member away from the first-mentioned member and located between said member and the axis about which it 115 swings. 110

20. In a machine of the class described, a cutting block, a clamp for clamping the material to be cut which projects beyond the edge of said block, said clamp comprising a member adjacent to the block, a second member arranged to be swung toward and from the first member about an axis below the block, a spring tending normally to hold said second member in clamping position, and a treadle connected to said member for moving it out of clamping relation against the tension of said spring. 120 125

21. In a machine of the class described, a cutting block, a clamp for clamping the 130

material to be cut which projects beyond the edge of said block, said clamp comprising a member supported adjacent to said block, and a second member having a support arranged to turn about a horizontal axis below said block, means for maintaining said second member in clamping position, and a treadle mounted upon said support and adjustable to bring its tread into different elevations.

22. In a machine of the class described, a cutting block, a cutting block stand, a clamp for clamping the material to be cut which projects beyond the block, said clamp comprising a member supported adjacent to the block upon said stand, a trough for holding the material which extends through the clamp, said trough being carried by said stand, and a second clamp member having a support fulcrumed upon said stand below said trough, whereby said second member may be swung into and out of clamping relation to said first-mentioned clamp member to clamp material of any width extending between said clamp members.

23. In a machine for cutting flexible sheet material, the combination with a cutting block, of means for clamping a portion of the material to be cut which projects beyond the edge of the block to prevent movement of the material on the block, said means comprising members relatively movable to clamp or release the material and constructed to permit the material to project lengthwise of the block beyond the ends of said members, one of said members having a curved surface over which the material passes to the cutting block and from which it depends as the stock supply for successive operations.

24. In a machine for cutting flexible sheet material, the combination with a cutting block, of means for clamping a portion of the material to be cut which projects beyond the edge of the block, said means comprising clamp members extending lengthwise of the block and limited in length to prevent them from projecting materially beyond the ends of the block, said clamping means being open at its ends to permit the

use of material of greater width than the length of the block and being provided with a smooth surface over which the material passes to the cutting block and from which it depends as the stock supply for successive operations.

25. An attachment for use with a cutting table comprising a clamp member having a smooth surface over which the material passes to the table, said clamp member being adapted for attachment to the frame of the table, and a second clamp member designed for pivotal mounting upon the support or frame of the cutting table and arranged to coöperate with the first-mentioned clamp member to hold the material to be cut upon said cutting table.

26. An attachment for use with a cutting block comprising an open-ended clamp having a curved surface over which the material passes to the cutting block and from which it depends as the immediate stock supply for successive operations, and means for detachably securing the clamp to the support or frame of the cutting block.

27. An attachment for use with a cutting table comprising an open-ended clamp having a curved surface over which the material passes to the cutting table and from which it depends as the immediate stock supply for successive operations, an open-ended trough to receive a supply of material to be operated on, and means for detachably securing the clamp and trough to the support or frame of the table.

28. An attachment for use with a cutting block comprising a clamp member over which the material passes to the cutting block, said clamp member being adapted for attachment to the cutting block, a coöperating clamp member designed for detachable, pivotal mounting upon the supports for the cutting block, and a trough for a supply of material to be operated upon, said trough having means to engage detachably horizontal and upright portions of the frame or support for the cutting block.

In testimony whereof I have signed my name to this specification.

FREDERICK H. SHERMAN.

It is hereby certified that in Letters Patent No. 1,279,595, granted September 24, 1918, upon the application of Frederick H. Sherman, of Whitman, Massachusetts, for an improvement in "Cutting-Machines," errors appear in the printed specification requiring correction as follows: Page 2, line 108, for the word "This," commencing with a capital "T," read *this*, to form a part of the last clause of the sentence; page 4, line 48, claim 13, for the word "provided" read *to provide*; and that the said Letters Patent should be read with these corrections therein that the same may conform to the record of the case in the Patent Office.

Signed and sealed this 20th day of May, A. D., 1919.

[SEAL.]

R. F. WHITEHEAD,

Acting Commissioner of Patents.
